UNITED STATES PATENT OFFICE.

WILLIAM SUBLETT, OF SAN FRANCISCO, CALIFORNIA.

CARTRIDGE.

SPECIFICATION forming part of Letters Patent No. 317,041, dated May 5, 1885.

Application filed January 22, 1885. (No model.)

To all whom it may concern:

Be it known that I, WILLIAM SUBLETT, of the city and county of San Francisco, State of California, have invented in Improvement in Loading Shotguns and Cartridges; and I hereby declare the following to be a full, clear, and exact description of the same.

My invention relates to an improved method of loading shotguns or shot-cartridges; and it consists in the employment of metallic or other wads and a metallic cylindrical case with sides either open or closed, within which the shot are contained and kept together until after they leave the gun.

Referring to the accompanying drawings for a more complete explanation of my invention, Figure 1 is a longitudinal section of a cartridge loaded by my method. Figs. 2 and 4 are views of the shot-inclosing case. Figs. 3 and 5 are views of the wads.

Where shot are to be used in hunting, it is desirable to keep them in a compact body some little time after they leave the muzzle of the gun in order to increase the range and penetration. In order to do this, I employ, first, a metallic wad, A, which is fitted to the bore of the gun and the interior of the cartridge-shell, when one is used, and this wad is forced down upon the powder. The shot are placed within a short metallic cylinder, B, which is made of a size just sufficient to go into the shell or barrel of the gun. The edges at the ends of this cylinder are preferably turned outward, as shown in Fig. 2, so that the central portion of the cylinder does not come in contact with the interior of the barrel, and these edges or flanges serve to keep the interior of the gun clear as they pass out-

ward at each discharge. The longitudinal meeting edges of the cylinder are not joined together, but are simply brought together so as to meet, and when the charge leaves the gun the cylinder will be spread apart, so as to allow the shot to escape.

The metallic wad before described may in some cases be used independently of the inclosing-cylinder, and it may be made flat or concave, as shown in Fig. 3. When made in this latter form, it assists in holding the shot in a body for a short distance after leaving the muzzle of the gun, and, if desired, it may be used without the cylinder with good results. The edges of this wad will also serve to clean the inside of the gun by scraping off the deposit after each discharge.

It will be manifest that this device may be used upon guns or cannon of any caliber with equally good results, and the wads or cases may be varied in their composition, shape, or construction without materially altering the character of my invention.

Having thus described my invention, what I claim as new, and desire to secure by Letters Patent, is—

In a cartridge for shotguns, a powder-chamber, and a cylinder containing the shot having outwardly-turned flanges at its ends, and a metallic wad intervening between the shot and the powder, substantially as herein described.

It witness whereof I have hereunto set my hand.

WILLIAM SUBLETT.
